(57) **CLAIM**

The ornamental design of a NMR spectrometer, as shown and described.

DESCRIPTION

FIG. 1 is a front perspective view of a NMR spectrometer; FIG. 2 is a rear perspective view of the NMR spectrometer of FIG. 1;

FIG. 3 is a front view of the NMR spectrometer of FIG. 1; FIG. 4 is a rear view of the NMR spectrometer of FIG. 1; FIG. 5 is a bottom view of the NMR spectrometer of FIG. 1;

FIG. 6 is a top view of the NMR spectrometer of FIG. 1; and, FIG. 7 is a side view of the NMR spectrometer of FIG. 1. The broken lines shown are included for the purpose of illustrating portions of the NMR spectrometer that form no part of the claim.
